UNITED STATES PATENT OFFICE.

NINEVAH P. VANCE, OF JOHNSON CITY, TENNESSEE, ASSIGNOR OF ONE-THIRD TO
WILLIAM C. THORNTON, OF JOHNSON CITY, TENNESSEE.

AUTOMATIC RAILROAD-CROSSING SIGNAL.

Application filed September 5, 1923. Serial No. 661,068.

To all whom it may concern:

Be it known that I, NINEVAH P. VANCE, a citizen of the United States, residing at Johnson City, in the county of Washington and State of Tennessee, have invented certain new and useful Improvements in Automatic Railroad-Crossing Signals, of which the following is a specification.

This invention relates to an automatic railroad crossing signal and alarm, and has for an object the provision of means whereby the train wheels, in passing along the rails within a predetermined distance of the road crossing, operates instrumentalities for displaying a visual danger signal and sounding an audible alarm.

Another object of this invention is to provide automatic means for cooperating with the wheels of a train as it passes from the signal zone for restoring the visual signal to its normal or housed position, silencing the audible alarm, and setting the device for automatic cooperation with trains which are traveling in either direction.

A further object of this invention is to provide a railroad crossing signal and alarm in which the movement of the visual signal establishes and breaks an electrical circuit for operating an additional signal and alarm.

An additional object of this invention is to provide an automatic railroad signal and alarm constructed to cooperate with trains of all lengths, thereby insuring the device against injury when operated by a train longer than the distance between the terminals of the signal zone.

It is also an object of this invention to provide an automatic railroad signal and alarm of generally improved construction, whereby the device will be simple, durable and inexpensive in construction, as well as efficient, positive and practical in its use.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

The invention has been illustrated in its 55 preferred embodiments in the accompanying drawings, wherein:

Figure 1 is an elevation of the device showing the signal board in its displayed position, and the housing for the spaced 60 shafts and disks being removed;

Figure 2 is a plan view of the device, said housings being removed;

Figure 3 is a fragmental longitudinal sectional view depicting the operative relation 65 between spaced primary and secondary movable members;

Figure 4 is a fragmental transverse sectional view taken on the line 4—4 of Figure 1, remote parts being omitted; 70

Figure 5 is an enlarged detail sectional view taken on the line 5—5 of Figure 3;

Figure 6 is an enlarged transverse sectional view taken on the line 6—6 of Figure 1. 75

Figure 7 is a fragmental vertical sectional view taken through the sign housing and showing the cooperative relation between the movable signal board and the electric circuit; 80

Figure 8 is a diagrammatic view of the electric circuit;

Figure 9 is an elevation of a mechanically operated audible alarm, parts being broken away; 85

Referring to the drawings, there is shown the usual railroad construction comprising the rails R, cross ties T, and a roadway or street S is depicted as crossing the railway.

Spaced posts 10 are erected adjacent the intersection of the railway and roadway and positioned at opposed sides of this roadway S. A rectangular housing 11 is secured to the posts 10 a suitable distance above the roadway, and includes spaced side walls 11^a, end walls 11^b, and top 11^c. The bottom of the housing 11 is open, as shown at 12, to slidably receive a rectangular sign or signal-board 13.

Cables 14 are secured to the opposed end of the signal-board 13 and extend upwardly through tubular guide members 15 and are trained around and secured within annular grooves 16 of composite pulleys or sheaves 17. These pulleys 17 are mounted on rollers 18 which rotate about spindles 19, and each spindle is secured at its inner end to a supporting plate 20 suitably secured to the posts 100 105

10, and the outer ends of these spindles are supported by brackets 21 carried by the plates 20.

In order to insure a uniform movement of 5 the opposed ends of the signal-board 13, the pulleys 17 are operably connected by a crossed cable 22 which is received within grooves 23 formed in these pulleys and causes them to rotate in synchronism but in 10 opposed directions. Grooves 24 are also formed in the periphery of the pulleys 17 for the reception of cables or flexible elements 25, and these cables are trained over pulley 26 journaled on posts 27 which are 15 positioned at the opposed terminals of the signal zone.

The pulleys 26 are journaled on roller bearings 28 supported by plates 29 and brackets 30 similar to those carried by the 20 posts 10. Small pulleys 31 are carried by the pulleys 26 and these relatively small pulleys are operably connected to pulleys 32 by cables 33, and these cables are interrupted by helical extension springs or other 25 yielding means 34, for the purpose which will be hereinafter disclosed.

Each pulley 32 is secured to a horizontal shaft 35 which is journaled in spaced bearings 36, carried by ground bars or sills 37. 30 An enlargement 38 is formed intermediate the ends of each shaft 35, and one end of a lever 39 is loosely mounted for rotation upon this enlargement. A squared or rectangular portion 40 is formed on the shaft 35 adjacent the enlargement 38 and is positioned within a squared aperture 41 formed at the axis of a disk 42, and a shoulder 43 formed on the shaft 35 engages one face of this disk. Mounted upon the enlargement 35 35 is a securing disk 44 having a circular axial aperture 45 surrounding this enlargement, and the disks 42 and 44 are spaced apart by opposed segmental stop blocks or members 46 which are secured between the 40 disks by bolts or other securing devices. The segmental stop members 46 are disposed in diametrical opposition and define segmental recesses 47 therebetween to permit a limited free movement of the lever upon the 45 shaft relative to the stop members and disks. A portion of the cylindrical enlargement 38 is threaded for the reception of a nut 48 which engages the outer face of the disk 44, thereby rigidly securing the disks 42 and 50 44 upon the shaft 35. The free end of each lever is positioned adjacent one of the rails R and extends a suitable distance above the rail in a portion to cooperate with the flange of the ordinary car or engine wheel W, and 55 this lever is normally held in a vertical position by opposed helical springs 49, which are attached at their inner terminals to the lever 39, and are secured at their outer ends to spaced cross timbers or supports 50 carried by the sills 37. Since the levers 39 are

positioned in the path of travel of the train and are moved by the train independently of the disks 42 and 44, these levers provide primary movable members positioned for predetermined cooperation with composite 70 secondary movable members including the disks 42 and 44 and the shafts 35.

A housing 51 incloses the shaft 35, pulley 32 and the disks, and each housing is provided with an elongated slot 52 through 75 which the lever 39 operates, while apertures 53 are provided to permit the cable 33 to pass therethrough.

The signal-board may be provided with any suitable illuminating means, and there 80 is shown an electric lamp 54 secured in a bracket 55 carried by the lower end of the signal-board. Electrical conductors 56 and 57 lead from the lamp to terminal contact pieces 58. These contact pieces 58 are positioned in the end edge of the signal-board adjacent the upper terminal thereof, and have their outer faces exposed to cooperate with spring terminal fingers 59 which are carried by the housing 11 in the path of travel of the contact pieces 58 and are electrically connected to conductors 60 and 61, the conductor 60 leading to one side of an electric alarm bell 62, while the conductor 61 leads to a storage battery or other source 90 of electric supply 63. The alarm bell 62 is preferably carried by the signal-board housing 11 and the storage battery is supported within an enclosure 64 carried by the post 10, and a conductor 65 leads from the bell 62 to the battery 63. A switch 66 is interposed in the line of the conductor 65 and is preferably positioned within the enclosure 64, to which access may be gained by a hinged door or closure 64a. 105

In operation, assuming that a train is travelling towards the right, in Figure 1, and the wheels W engage the left lever or primary movable member 39 and move it about its fulcrum towards the right. This 110 action causes this lever to engage its segmental stop 46 and move it to the position shown in dotted lines, at 67, in Figure 3, thereby rotating the shaft 35, disks 42 and 44 and the pulley 32 towards the right, 115 which in turn rotates the disks 42 and 44, at the right end of the signal zone, toward the left through the instrumentality of the interposed pulley and cables, which have been described. Since the pulleys 17 rotate in synchronism but in opposed directions, it is obvious that the signal-board 13 will be lowered from the housing in a horizontal position, where it will display any preferred 120 warning sign, and in the present instance the word "Danger" is inscribed thereon. When the signal-board 13 reaches its lowermost position, then the contact pieces 58 will contact with the spring fingers 59 and complete the electric circuit, thereby causing 125 130

the alarm bell to ring and the signal lamp to light. The signal remains in this condition until the train reaches the right end of the signal zone where it engages the right lever 39 and rotates it to the dotted position shown at 68 in Figure 3. This action elevates the signal-board 13 to its housed position and resets the entire device so that it may again be operated by trains travelling in either direction. As the signal-board moves upwardly it causes the contact pieces 58 to disengage the fingers 59 and breaks the electric circuit, thus silencing the alarm bell and extinguishing the signal light.

If a train of unusual length, or one which is longer than the length of the signal zone, should pass along the rails and operate the right lever 39 while the left lever is depressed, then the right spring 34 of the cables 33 will yield and permit the components to operate without injury to the device. When the train wheels disengages the levers 39, they, under the influence of the springs 49, will be returned to their vertical or set position. Since the pulleys 31 are smaller than the pulleys 26, it is obvious that on a slight rotation of the lever 39 will impart an increased movement to the signal-board to lower it to its displayed position.

A mechanically operated alarm device is shown in Figure 9, and comprises a pulley 17^a journaled on a post 10^a and having a plurality of pins or projections 69 extending from one face thereof and positioned to cooperate with the terminal of a swinging arm 70. The arm 70 is pivoted within a bell 71 at the axis thereof, and extends through a slot 72 formed at the periphery of the bell 71.

Bowed spring members 73 are secured to the arm 70 adjacent its pivotal point, and these spring members 73 carry clappers 74 at their outer ends. The arm 70 is normally held in a vertical position by opposed springs 75 which are secured to brackets 76 carried by the posts 10^a.

When the pulley 17^a is rotated, a pin 69 moves the outer end of the arm to one side about its pivot until this pin 69 moves from engagement with the arm 70. Now one of the springs 75 violently pulls the arm back towards its vertical position and this sudden movement of the arm 70 about its pivot causes the clappers 74, in response to centrifugal action, to impinge against the peripheral portion of the bell thereby sounding the alarm bell.

Having thus described my invention, what I claim as new is:

1. An automatic railroad crossing signal including a secondary movable member positioned at one terminal of a signal zone, a signal member, means for operably connecting the signal member and the secondary

movable member, a primary movable member normally positioned in the path of travel of the train and operably associated with the secondary movable member to operate the signal member when the primary movable member is operated by the moving train, the primary movable member being movable independently of the secondary movable member during phases of its operation, and means for moving the primary movable member to its normal position independently of the secondary movable member.

2. An automatic railroad crossing signal including a secondary movable member positioned at one terminal of a signal zone, a signal member, yielding means for operably connecting the signal member with the secondary movable member, a primary movable member normally positioned in the path of travel of the train and operably associated with the secondary movable member to operate the signal member when the primary movable member is operated by the moving train, means for moving the primary movable member to its normal position independently of the secondary movable member.

3. An automatic railroad crossing signal including a secondary movable member positioned at the entrance of a signal zone, an alarm signal, means for operably connecting the signal with the secondary movable member, a primary movable member normally positioned in the path of travel of the train and operably associated with the secondary movable member to put the signal in alarm condition when the primary movable member is operated by the train in entering the signal zone, a secondary movable member positioned at the outlet of the signal zone and operably connected with the signal, a primary movable member normally positioned in the path of travel of the train at the outlet of the signal zone and operably associated with this secondary movable member to restore the alarm signal to normal condition when this primary movable member is operated by the train in leaving the signal zone, said primary movable members being movable independently of the secondary movable members during phases of their operation, and means for moving the primary movable members to their normal position independently of the secondary movable members.

4. An automatic railroad crossing signal including a secondary movable member positioned at the entrance of a signal zone, an alarm signal, yielding means for operably connecting the signal with the secondary movable member, a primary movable member normally positioned in the path of travel of the train and operably associated with the secondary movable member to put the

- signal in alarm condition when the primary movable member is operated by the train in entering the signal zone, a secondary movable member positioned at the outlet of the signal zone, yielding means for operably connecting the secondary movable member which is positioned at the outlet of the signal zone with the signal, a primary movable member normally positioned in the path of travel of the train at the outlet of the signal zone and operably associated with this secondary movable member to restore the alarm signal to normal condition when this primary movable member is operated by the train in leaving the signal zone, said primary movable member being movable independently of the secondary movable members during phases of their operation, and means for moving the primary movable members to their normal position independently of the secondary movable members.
5. An automatic railroad crossing signal including a secondary movable member positioned at each terminal of a signal zone, an alarm signal, means for operably connecting each secondary movable member to the said signal, a primary movable member normally positioned in the path of travel of the train and operably associated with each secondary movable member, and yielding means for moving each primary movable member to its normal position independently of the cooperating secondary movable member.
35. An automatic railroad crossing signal including a rotatable shaft, a lever fulcrumed adjacent to the axis of the shaft and movable independently of the shaft, means for normally maintaining the lever in the path of travel of the train, stop members rigidly supported relative to the shaft and positioned in the path of movement of the lever to limit the independent movement of the lever and to be engaged by the lever to rotate the shaft during predetermined phases of operation of the lever, an alarm signal, and means for operably connecting the alarm signal and the shaft to operate the alarm signal.
40. An automatic railroad crossing signal including separate rotatable shafts, a lever loosely mounted upon each shaft and positioned in the path of travel of the train, a disk rigidly secured to each shaft and positioned adjacent the levers, stop members carried by the disk and positioned to cooperate with the levers to permit a limited movement of the levers independently of the disks and to be engaged by the levers to move the disks during predetermined phases of operation of the levers, means for normally maintaining the levers in set positions, a visual signal, and means for operably connecting the said shafts and the
- visual signal to move the signal to and from displayed position when the said levers are moved by their engagement with the moving train.
8. An automatic railroad crossing signal including spaced rotatable shafts, levers loosely mounted upon the shafts and positioned in the path of travel of the train, disks rigidly secured to the shafts and positioned adjacent to the levers, pulleys carried by the shafts, a visual signal supported in spaced relation to the shafts, pulleys supported in cooperable relation to the visual signal, flexible elements trained over the pulleys and operably connecting the visual signal and the rotatable shafts, means for normally holding the levers in their set positions in the path of travel of the train, and stop members carried by the disk to cooperate with the levers to move the visual signal to its displayed and undisplayed positions when the lever is moved by engagement with the moving train to impart motion to the said disks.
9. An automatic railroad crossing signal including a rotatable shaft, a lever fulcrumed adjacent the axis of the shaft and movable independently of the shaft, means for normally maintaining the lever in the path of travel of the train, stop members supported by the shaft and positioned in the path of movement of the lever to limit the independent movement of the lever and to be engaged by the lever to rotate the shaft during predetermined phases of operation of the lever, an alarm signal, and means for operably connecting the alarm signal and the shaft to operate the alarm signal.
10. An automatic railroad crossing signal including a rotatable shaft positioned at the entrance of a signal zone, an alarm signal, means for operably connecting the signal and the shaft, a lever fulcrumed adjacent the axis of the shaft and normally positioned in the path of travel of the train, stop members rigidly supported relative to the shaft and positioned in the path of movement of the lever, said lever engaging the stop member to put the signal in alarm condition when the lever is engaged by the train in entering the signal zone, a rotatable shaft positioned at the outlet of the signal zone and operably connected with the alarm signal, a lever operably associated with the shaft which is positioned at the outlet of the signal zone to restore the signal to normal condition when this lever is operated by the train in leaving the signal zone, said levers being movable independently of the shafts during phases of their operation.
- In testimony whereof I affix my signature.
- NINEVAH P. VANCE.
